(57) **CLAIM**

I claim the ornamental design for a cigarette package, as shown and described.

DESCRIPTION

FIG. 1 shows an isometric view of the invention with a partially closed lid.

FIG. 2 shows an isometric view of the invention with an open lid; and,

FIG. 3 shows an isometric view of the invention with an expanded view of the closing sticker and box top.

The broken lines in the drawings depict portions of the cigarette package that form no part of the claimed design.
